DESIGN FOR A CAP COVER

Paul M. Maxwell, Manhasset, N. Y., and Wilhelmina J. Russy, Jersey City, N. J., assignors to Hat Corporation of America, Norwalk, Conn., a corporation of Delaware

Application December 18, 1944, Serial No. 116,983

Term of patent 7 years

(CL. D3—13)

To all whom it may concern:

Be it known that we, Paul M. Maxwell and Wilhelmina J. Russy, each a citizen of the United States, residing respectively, at Manhasset, county of Nassau, and State of New York, and at Jersey City, county of Hudson, and State of New Jersey, have invented a new, original, and ornamental Design for Cap Covers, of which the following is a specification, reference being had to the accompanying drawing, forming part thereof.

Fig. 2 is a side view thereof.

Fig. 3 is a rear view thereof.

The design of the cap cover illustrated is characterized by the diagonal seam on the sides thereof extending from the top back to the tie under the chin specifically as shown.

We claim:

The ornamental design for a cap cover, as shown and described.

PAUL M. MAXWELL.

WILHELMINA J. RUSSY.
